UNITED STATES PATENT OFFICE

ALBERT EDWIN BRADLEY, OF WILMERDING, PENNSYLVANIA.

HAT-PIN.

No. 802,841.

Specification of Letters Patent.

Application filed March 6, 1905. Serial No. 248,600.

Patented Oct. 24, 1905.

To all whom it may concern:

Be it known that I, ALBERT EDWIN BRADLEY, a citizen of the United States of America, residing at Wilmerding, in the county of Allegheny and State of Pennsylvania, have invented certain new and useful Improvements in Hat-Pins, of which the following is a specification, reference being had therein to the accompanying drawings.

10 This invention has relation to hat-pins; and it has for its object the provision of novel means for securing the pin in position in a hat.

15 My invention consists, primarily, of a hat-pin which carries adjacent the head a novel form of spring-catch having a free end which will yield readily under pressure both in the insertion and withdrawal of the pin and which at the same time will effectually retain the pin 20 from accidental displacement.

My invention further consists in details of construction hereinafter set forth and claimed.

My invention is illustrated in the accompanying drawings, wherein—

25 Figure 1 is a side view of a hat-pin constructed according to my invention. Fig. 2 is a fragmentary view of a portion of the pin on an enlarged scale. Fig. 3 is a transverse sectional view of a modified form of my improvement. Fig. 4 is a fragmentary view, on an enlarged scale, in section, of a further modification of my invention; and Fig. 5 is a transverse sectional view on the line 5—5 of Fig. 2.

30 The pin 1 in my improvement is provided with the usual ornamental head 2, which may of course be of any desired size and configuration. In order to retain the pin in the hat, I form the pin with a spring-tongue 3, which is preferably made integral with the body of 35 the pin and has one end 4 free, while the other end 5 is fast, being united to the pin at that point.

35 In the preferable form of my improvement the spring-catch 3, which is in the form of a bow or arc and which at its center is raised slightly above the surface of the pin, is formed by cutting a sliver or tongue out of the body of the pin by means of a suitable tool, this tongue being, as illustrated in Figs. 1 and 2, 40 integrally united with the pin at one end and free at the other end, the free end 4 resting in the slot which is formed by cutting out the

tongue. After the tongue has been cut out from the body of the pin it is bent to the shape shown in the drawings or to other 55 equivalent form and constitutes a spring-catch which when the pin is inserted in a hat will lie inside the hat and prevent the pin from falling out or being accidentally displaced.

50 In the form shown in Fig. 3 instead of cutting the tongue 3 out of the body of the pin and leaving a slot beneath the tongue, as illustrated in Fig. 5, I form the tongue by making a straight cut transversely of the pin near one side thereof, thus leaving the tongue 3 65 with a flat lower side 6 and the pin with a flat surface 7 below the tongue. In the modification shown in Fig. 4, which is applicable to either of the forms of tongues shown in Figs. 2 and 3, I position the fast end of the tongue 70 away from the head and the free end of the same adjacent the rear side of the head 2, the head, for the purpose of providing a socket for the free end of the tongue, being formed with a recess 8, in which the free end of the 75 tongue will rest, so as to prevent the said free end from being engaged with the inner edge of the hole in the hat through which the pin passes. The pin is used in the ordinary manner—that is, it is pushed through the hat and 80 through the hair of the wearer—and when it has been pushed through the hat the spring-tongue 3, being inside the hat, will prevent the pin from falling out, this tongue being depressed and straightened out into alignment 85 with the body of the pin when the pin is inserted. The pin is drawn out by grasping the head in the hand and pulling it outwardly in the usual manner, the tongue 3 during this operation being depressed by the edge of the 90 hole in the hat, so as to permit the pin to be pulled out by the exercise of a little force.

What I claim, and desire to secure by Letters Patent, is—

1. A hat-pin formed adjacent its head with 95 a longitudinal groove, said pin being provided with a spring-tongue of arc-shaped curvature seated in said groove, one end of said tongue being fast to the body of the pin, and the other end of the tongue being free and having a limited movement under pressure in said groove.

2. A hat-pin provided adjacent its head with a longitudinal groove formed by cutting from

the body of the pin a spring-tongue which is bent into arc-shaped curvature, one of the ends of said tongue being integral with the body of the pin and the other end being free and 5 resting in said groove and having a limited movement therein, when said tongue is depressed.

In testimony whereof I affix my signature in the presence of two witnesses.

ALBERT EDWIN BRADLEY.
